J. S. RICHARDSON.

Churn.

No. 8,146.

Patented June 10, 1851.

UNITED STATES PATENT OFFICE.

I. S. RICHARDSON, OF BOSTON, MASSACHUSETTS.

CHURN.

Specification of Letters Patent No. 8,146, dated June 10, 1851.

To all whom it may concern:

Be it known that I, ITHIEL S. RICHARDSON, of Boston, in the county of Suffolk and Commonwealth of Massachusetts, have invented a new and useful Improvement in the Churn, denominated the "Oscillating Perpendicular Dash-Churn;" and I do hereby declare, the following is a full, clear, and exact description of the construction and operation of the same, reference being had to the annexed drawings, making a part of this specification.

The parts in the drawing, marked by the letter A, are the standards, $2\frac{1}{2}$ by $1\frac{1}{2}$ inches square and four feet long, fastened together at the top, spreading $3\frac{1}{2}$ feet at the bottom and set upright in pairs 16 inches apart.

The letter B designates the parts of a frame fastened to the standards on the outside, for the purpose of steadyng the same.

C indicates the parts of the swing or pendulum-frame, which is made of three pieces of board, one 12 by 16 inches square, is fastened to the lower ends of the two upright pieces which are 2 inches wide at top, and 4 inches wide at bottom. These upright pieces hang from a rod which passes through them near their tops, and also through the standards, at the parts where they unite at top, to which the letter D has reference. The rod D has in its middle portion a bend (somewhat like the letter U placed between two horizontal lines, which meet its upper parts) which bend is represented by the Figure 3, of the drawing; and is made for the purpose of permitting the movement of the parts marked F and G, to be hereinafter described.

The letter E refers to the tank or cistern for containing the cream or milk, and is suspended in the pendulum frame C. The dash stick F, is coupled with the lever G by means of a pin, which is shown in the Fig. 3 in a manner that needs no reference. The other end of the lever G is firmly fixed in the middle of the rock shaft pointed out by the letter H, which rock shaft has its bearings or points of support in the upper extremities of the two diagonal frame cross pieces marked with the letter I. These cross pieces, are fastened on the outside of the supporters or standards and with them and the parts marked B constitute the fixed frame of the apparatus. Near one end of the rock shaft is firmly fixed another lever marked J, which extends perpendicularly

down to the connecting rod marked K, with which it is coupled by means of a pin, the head of which is shown in the drawing. The connecting rod is also coupled at its other extremity, with one of the upright pieces of the swing C by a similar pin, both pins being movable for the purpose of making connection higher or lower, as shown by dotted lines Figs. 1 and 2. The parts G H J together are a bent lever, the extremity of G moving vertically and the extremity of J moving horizontally, the fulcrum being in the bearings of H.

L marks a rod coupled with the lower part of the swing, by means of a hook and staple, for communicating motion from the hand or otherwise, to the swing C. The motion of the swing is communicated from one of its upright pieces, through the connecting rod K to the bent lever G H J, which changing the motion from horizontal to vertical, communicates it to the dash stick F, which dash stick may have greater or less extent of motion given it, by raising or lowering the coupling between the lever J, and connecting rod K, or by lowering or raising the coupling between the connecting rod K and the upright part of the swing C.

The parts in Figs. 1, 2, and 3, of the drawing, that are lettered similarly are the same. Fig. 1 exhibits a side elevation of the apparatus. In Fig. 2, the visible portions of the fixed frame seen in Fig. 1, together with one of the upright parts of the swing C, are removed, showing in outline similar parts of the frame that were obscured in Fig. 1, and one of the upright pieces of the swing C; exhibiting also a section of the rod D, the tank E, the bottom part of the swing C', the dash stick F, and appendages to be hereinafter described; but in other respects Figs. 1 and 2 are alike in all parts described. In the description of the rod D, reference has been made to Fig. 3, which represents the rod D in its relation to other parts, as seen by looking down upon the top of the apparatus.

The parts remaining to be described, as seen in Fig. 2, are as follows: M the dasher, is securely fixed at the lower end of the dash stick F. N a false bottom, perforated with a number of holes as shown in the section of Fig. 2 is secured in its place by a movable wedge O, which extends up to near the top of the tank to be easily accessible; the position of the wedge being such that it does not

come in contact with the extended parts of the dasher. In the center of the false bottom is fastened a staff or handle which runs up into a cavity of cylindrical form, in the center of the dash stick, which cylindrical cavity extends up about 12 inches or above the top of the tank, when the parts are at rest; near the termination of the cavity is made an opening from the outside, in which 5 is inserted a perforated plug having a valve at its inner end as shown at Q. R refers to the shoulder on the inside of the tank near its top on which the cover rests.

The following is the manner in which the 10 above described apparatus operates. All the parts being *in situ*, the material to be acted upon is poured into the tank, over which the cover is placed. The hand holding the rod L communicates a backward and forward motion 15 to the swing, which motion the swing, communicates from one of its upright parts, through the connecting rod K to the arm J of the bent lever G H J, which bent lever, from its arm G, gives the motion to the dash 20 stick F, and by reference to the drawing, it will be seen that as the movement of the swing is to the left, the dash stick raises, and as the movement of the swing is to the right the dash stick falls. At each 25 elevation of the dash stick, the cavity therein is increased, by its being drawn away from the staff P, and to prevent a vacuum being formed in the cavity (thereby retarding the motion) the air is permitted 30 to enter the perforated plug at Q, and as the dash-stick is depressed, the valve operates to retain the air therein, and as its space is diminished by the falling of the dasher, it escapes downward along the space in the 35 cylindrical cavity, in the dash stick around the staff P, where, by its elasticity, its presence under the dasher prevents the tendency to vacuum consequent to the succeeding upward motion of the dasher. In the top of 40 the dash stick E, may be 2 or more holes, for the purpose of inserting the coupling pin 45

that connects the dash stick and lever G, in order to bring the dasher nearer the bottom of the tank, to accommodate the capacity of the apparatus to a smaller quantity of material; and in such case in order to confine the movements of the dasher to the limits of the material to be acted on, the coupling between the connecting rod K, and the lever J, may be put lower, or the coupling that unites 50 the other end of the connecting rod with the upright part of the swing, may be put higher; either or both of which adjustments may be made to shorten the motion of the dasher, if there be need.

Having effected the desired changes upon the contents of the tank, the rod L may be unhooked, the coupling pin at the top of the dash stick, that connects it to the lever G, may be taken out, and the tank with its contents removed from the swing to a more accessible position. The cover being now taken off, permits the removal of the dasher. The wedge O being withdrawn, frees the 60 false bottom N, which by taking hold of the staff P, may be drawn slowly upward, bringing with it the butter, permitting the buttermilk to drain back into the tank through the perforations mentioned in the previous description of the false bottom N; and in this 65 capacity the false bottom N, may be considered a strainer, for separating the butter from the buttermilk.

Now, what I claim as my invention, and desire to secure by Letters Patent, is,

The combination of the rock shaft, levers, connecting rod, and swing for the churn, for the purpose of producing the perpendicular movement of the dasher substantially in the manner herein described; to be 70 75 80 85 denominated "the oscillating perpendicular dash churn."

I. S. RICHARDSON.
